UNITED STATES PATENT OFFICE.

THOMAS EDMUND HOLMES, OF NETHER EDGE, SHEFFIELD, ENGLAND, ASSIGNOR TO
UNITED ENGINEERING & FOUNDRY COMPANY, OF PITTSBURGH, PENNSYLVANIA,
A CORPORATION OF PENNSYLVANIA.

APPARATUS FOR ROLLING HOOPS OR TIRES.

1,165,175.

Specification of Letters Patent.

Patented Dec. 21, 1915.

Application filed August 10, 1914. Serial No. 856,051.

To all whom it may concern:

Be it known that I, THOMAS EDMUND HOLMES, a subject of the King of England, and a resident of Nether Edge, in the county 5 of Sheffield, England, have invented a new and useful Improvement in Apparatus for Rolling Hoops or Tires; and I do hereby declare the following to be a full, clear, and exact description thereof.

10 My invention relates to apparatus for rolling wheel-tires or other metal hoops and for like purposes, of the type wherein the work is operated upon between inner and outer rolls which are mounted to turn about horizontal axes placed vertically one above the other, the rolls being so supported as to enable the distance between their respective axes of rotation to be varied as the thickness of the material pressed between them 15 diminishes.

The object of my present invention is to improve apparatus of this type in a number of different ways, whereby greater economy is effected in the operation of the apparatus, 20 and at the same time greater efficiency obtained due to the improved construction, all of which will be more fully hereinafter set forth and claimed.

In the accompanying drawings, Figure 1 25 is a longitudinal section of my improved apparatus; Fig. 2 is a plan view; Fig. 3 is a section along the line 3—3 Fig. 1; Fig. 4 is an enlarged sectional view of the manner of supporting the rolls and the adjustment 30 thereof; and Fig. 5 is a section on the line 5—5 Fig. 1.

In the drawing, the numeral 2 designates a suitable bed plate which is bolted or secured in the ordinary manner to the concrete 35 or other suitable foundation 3, and for purposes of convenience the bed-plate 2 is arranged at the bottom of the pit 4.

Supported on the bed-plate 2 and extending down into the foundation 3 is the cylinder 40 5 provided with the ram or plunger 6. Above the ram 6 is the vertically movable table 7 which is elevated by said ram, and, in order to provide against the canting of the movable table, I provide a parallel-motion device which consists of crank-arms 8 pivoted to the bed-plate 2, the arms 9 of said crank-arms being connected up to rods 10 pivotally connected to the table 7 as at 11. The arms 12 of the crank-arms 8 are con-

nected by the rod 13. It will be apparent 55 therefore that, although the ram 6 is located at one end of the table 7 a parallel motion will be imparted to the table 7 as it is raised so as to relieve the strain and the wear on the parts. To prevent horizontal whipping 60 of the table either longitudinally or transversely, adjustable guides are provided at the four corners, as shown in the sectional view Fig. 5, and for this purpose, the guide-bed 14 is provided at one end of said table 65 which connects the bed-plate 2 with the upper bed-plate 15. This guide-bed 14 has the guides 16 and said guides are provided with the adjustable pieces 17 which are held in place by the set-screws 18 so that when wear 70 occurs on the sliding surfaces between the table and said pieces 17, by slackening up on the screws 18 and inserting thin liners behind said pieces 17, and then tightening up said screws the wear is compensated for. 75 The other end of the table works in similar guides in the vertical standards 19, the wear-pieces 20 being held in place by set-screws 21, and the wear at this point may be compensated for in the same manner as above 80 set forth.

The table 7 has the end bearings 22 and the central bearing 23. The end bearings 22 form the support for the hollow spindle 24, said spindle having the flanged end portion 85 25. Within the spindle 24 is the roll-arbor 26 which carries at its outer end the roll 27. This roll 27 is the lower roll of the apparatus, and, where a flange is to be formed on the tire to be rolled, said roll 27 is provided with the shoulder 28. The arbor 26 is secured within the spindle 24, so as to rotate therewith by any suitable means, that illustrated consisting of the cotter 29 which is driven through openings in said spindle 90 and arbor, as clearly indicated in Fig. 4 in connection with the spindle and arbor of the upper roll 39.

The center bearing-block 23 has a tongue portion 31 which engages a groove 32 in the 100 table 7, and said bearing-block is further secured by the tie-bolts 33 to the bearing 22 nearest the rolls. Within the bearing-block 23 is the sleeve 34, said sleeve having the threaded portions 35 with which the ring-nuts 36 engage. These ring-nuts provide for the adjustment of the sleeve in its bearing, said sleeve surrounding the spindle 24.

This sleeve 34 takes the thrust of the spindle 24 due to the rolling operation and ball thrust-bearings 37 are provided between the flanged portion 38 of the spindle 24 and the 5 end of the sleeve 34 which is backed up by the lock-nuts 34^a. By this construction the horizontal adjustment of the spindle 24 may be effected by slackening one of the ring-nuts 35 and tightening up the other.

- 10 The upper roll 39 is mounted in the same manner as the lower roll 27, and the same reference numerals have been used to indicate the same parts as described in connection with the lower roll 27. In Fig. 4, however, the key 30 is shown in detail, said key being interposed between the inner end of the arbor 26 and the spindle 24 so that by changing the key 30 for one of different dimensions, the amount that the roll 39 projects beyond the spindle can be conveniently regulated and the amount of projection of the roll can be adjusted accurately. This same key is used in connection with the lower roll 27 although it is not deemed necessary 25 to illustrate it in connection with said lower roll. The rolls are driven independently of each other, from the outer end and in the case of the lower-roll, a universal spindle 40 with spherical ends 41 is interposed between 30 the spindle and the driving-shaft 42. This provides the necessary flexibility when the table 7 carrying the roll is raised into working position, as indicated in dotted lines, Fig. 1.
- 35 In order to support and steady the tire or hoop during rolling, two guide-rolls 43 are provided. In order to effect the adjustment of said guide-rolls, said guide-rolls are mounted at the outer end of the member 44 adapted to move back and forth in the guide 45. The threaded-bar 46 engages a threaded nut 47 in the member 44, and by turning said threaded bar the member 44 with the guide-roll 43 is advanced or withdrawn as desired.
- 45 To provide for the advancement and withdrawal of both of the guide-rolls 43 simultaneously, I provide the following mechanism: A hand-wheel 48 is mounted on the shaft 49 mounted in bearings in the pedestal 50. A beveled gear 51 on the shaft 49 meshes with the beveled gear 52 on the vertical shaft 53 passing down through the pedestal 50. At the lower end of the vertical shaft 53 is the beveled pinion 54 which 55 meshes with a beveled pinion 55 on the shaft 56. At one end of the shaft 56 is the beveled pinion 57 which meshes with the beveled pinion 58 on the end of the threaded bar 46. At the opposite end of the shaft 56 is the beveled pinion 59 which meshes with the beveled pinion 60 on the shaft 61. The shaft 61 extends over to the other side of the apparatus where the beveled pinion 62 carried by said shaft meshes with the beveled pinion 63 on the shaft 64. The beveled pinion 65

at the opposite end of said shaft 64 meshes with a beveled pinion 66 on the screw-bar 46 at that side of the machine. In this manner by rotating the hand-wheel 48 a simultaneous adjustment of the two rollers 43 is effected, and said rollers are moved in or out as may be necessary to properly support the tire according to its diameter.

When my improved apparatus is in use, the annular blank or disk to be rolled is placed on the roll-portion 39, and the lower roll is then raised by admitting motive fluid to the cylinder 5, whereby the ram is raised and the table 7 supported thereby is moved upwardly, the parallelism of said table being maintained by means of the bell-cranks 8 and the other connections hereinbefore described, so that said table moves without undue strain or wearing on the parts, and more especially the wear pieces 17 and 20 at 85 the corners thereof. The table is raised until the roll portion 27 comes into contact with the blank. Both rolls are then caused to revolve and the pressure which is brought to bear by the ram 6 on the blank causes the latter to expand diametrically as its thickness is reduced, but the width cannot increase beyond the amount determined by the distance between the flanges 25 of the spindles which overlap the rolls, as indicated in Fig. 4. By having the cylinder 6 arranged in the position indicated, the pressure applied by the ram and through the roll-portion 27 to the tire-blank is such that the center of load is in line with the center of pressure. This in connection with the parallelism maintained by the table in its movement relieves the guides of excessive loads which increases the efficiency of the machine and reduces the wear and tear.

By my invention, I provide for the adjustment of the rolls longitudinally, as well as the spindles, to provide against wear that takes place in the disks or flanges 25 and to adjust the distance between said disks which is necessary to produce tires with the correct width. This is due to the fact that the spindles are made hollow and the rolls inserted therein, said spindles being provided with means for adjustment and the rolls provided with the independent adjustment by means of the cotters 29 and the keys 30. By my invention with the use of one set of spindles, rolls with working portions of different sizes may be inserted in said spindles, and so reduce the cost of operation.

What I claim is:

1. In apparatus for rolling tires, hoops, etc., the combination of an inside upper roll, a lower outside roll movable to and from said upper roll, and means for applying pressure to said lower roll on a line with the center of load.
2. In apparatus for rolling tires, hoops, etc., the combination of an upper inside roll, a

lower outside roll movable toward said upper roll, and a cylinder in the path of said lower roll, the axial line of said cylinder being in line with the center of the load.

5 3. In apparatus for rolling tires, hoops, etc., the combination with an upper inside roll, a lower outside roll, a movable table supporting said lower roll, a cylinder, a ram in said cylinder engaging said table, the axial line of said ram being in line with the center of the load, and means for maintaining the parallelism of said table.

10 4. In apparatus for rolling tires, hoops, etc., the combination of an upper inside roll, a lower outside roll, a table, guides for said table, a cylinder, a ram in said cylinder engaging said table, the axial line of said ram being in line with the center of load, bell-crank connections between said bell-crank 15 and said table, and a rod connecting said bell-crank.

20 5. In apparatus for rolling tires, hoops, etc., the combination of a hollow spindle, a

roll arbor within said spindle, a roll-portion on said arbor projecting beyond said spindle, 25 said spindle having a flange at the outer end, and means for adjusting said roll arbor longitudinally in said spindle, and means for adjusting said spindle longitudinally and independently of said roll-arbor. 30

6. In apparatus for rolling tires, hoops, etc., the combination of a rotary hollow spindle, a roll-arbor contained therein having a roll-portion extending out beyond said spindle, said spindle having a flange at the 35 outer end thereof, a stationary sleeve surrounding said spindle forming a thrust bearing for the same, and means for adjusting said sleeve.

In testimony whereof, I the said THOMAS 40 EDMUND HOLMES, have hereunto set my hand.

THOMAS EDMUND HOLMES.
